UNITED STATES PATENT OFFICE.

HARRY GUEST, OF BILLERICA, MASSACHUSETTS, ASSIGNOR OF ONE-HALF TO GEORGE T. CLARK, OF LOWELL, MASSACHUSETTS.

LOCOMOTIVE CROSSHEAD.

Application filed December 16, 1925. Serial No. 75,835.

This invention relates to a locomotive cross-head constituting a connection between the piston-rod and the connecting-rod or pitman reciprocated thereby, the 5 cross-head including a body having means for connection with the piston-rod and pitman, and shoes removably seated on the upper and lower sides of the body and formed to slide on the usual cross-head guides, 10 securing means being provided for fixing the shoes to the body.

The object of the invention is to provide an improved construction of the body and shoes, and improved securing means rigidly 15 connecting the shoes with the body, whereby by the bolts heretofore employed are dispensed with, the well known objections incidental to the employment of said bolts including the loosening of the bolts by the 20 wear to which they are subjected, are obviated, and the number of parts, the cost of manufacture, and the time required for assembling and for compensating for wear, are reduced to a minimum.

25 Of the accompanying drawings forming a part of this specification,—

Figure 1 is a perspective view of the body of a cross-head embodying the invention.

Figure 2 is a perspective view of one of 30 the shoes.

Figure 3 is a transverse section showing the body and shoes assembled.

Figure 4 is a fragmentary section on line 4-4 of Figure 3.

35 Figure 5 is a section on line 5-5 of Figure 4.

Figure 6 is a perspective view, showing one form of the key hereinafter described.

Figure 7 is a fragmentary sectional view, 40 showing a different form of key.

Figure 8 is a perspective view of the key shown by Figure 7.

Figure 9 is a perspective view, showing a modification of the cross-head body.

45 Figure 10 is an end view, showing a modification of the shoe.

The same reference characters indicate the same parts in all of the figures.

Referring first to Figures 1 to 5, inclusive, 50 12 designates the body, and 13, 13 the shoes constituting members of a cross-head embodying the invention. The shoes and the portions of the body with which they co-operate are alike, so that a description of

one shoe and of the corresponding portion 55 of the body will suffice.

The body is provided with a longitudinally extending and longitudinally tapered groove, the bottom wall of which is designated in Figure 1 by 14, and the dovetail 60 edge walls by 15, said walls constituting a joint element. By "longitudinally tapered" I mean that the width of the groove increases from one end to the opposite end of the body, as shown by Figure 1. Extending 65 through the opposite side faces of the body and the edge walls 15, are alined slots 16.

On the inner face of the shoe is formed a longitudinally extending and longitudinally tapered dovetail rib 17, constituting a 70 joint element complementary to the joint element first described the width of the rib increasing from one end to the opposite end of the body, as shown by Figure 2. Said elements, when interengaged, confine the shoe 75 against sidewise movement outward from the body and permit separation of the shoe from the body by a longitudinal movement of the shoe in one direction only, indicated by the arrow X. The longitudinal taper of 80 the joint elements confines the shoe member against endwise movement in one direction from a predetermined position on the body member, and permits removal of the shoe member by an endwise movement thereof, 85 in the opposite direction. The continuity of the rib 17 is interrupted by a transverse keyway 18 (Figure 2), which registers with the slots 16, when the shoe is in said predetermined position, which is its operative position on the body.

20 designates a tapered key, insertible in said keyway and slots, and conforming to the taper of the keyway.

I provide means for longitudinally adjusting the key, to cause its oblique edges to bind on the oblique walls of the keyway, and for confining the key in the adjusted position. The key when thus confined confines the shoe member in the predetermined 95 operative position which it assumes when the edge walls of the tapered rib bear on the edge walls of the tapered groove and prevents endwise movement of the shoe relative to the body in the direction permitted 100 by the longitudinal taper of the rib and groove when the key is removed. Sidewise movement of the shoe outward from the 105

body is at the same time prevented by the interengagement of the dovetail rib 17, with the dovetail groove in the body.

The means for longitudinally adjusting and confining the key may be variously embodied, as shown by Figures 3, 5, 6, and 7. The key may be provided with a threaded shank 21, projecting from one of its ends, and with a nut 22, engaged with the shank and adapted to be set up against one of the side faces of the body 12, and thus exert a pulling force on the key in the direction required to cause the binding of the oblique edges of the key on the oblique side walls 15 of the keyway.

The alternative means shown by Figures 7 and 8, includes an ear 23, formed on one end of the key and provided with an orifice 24 (Figure 8) and a headed screw 25, engaged with a tapped socket in the body 12, the screw passing through the orifice 24, and its head bearing on the outer side of the ear, so that, when the screw is adjusted inward, its head exerts pressure on the ear in the direction required to cause the binding of the edges of the key on the side walls of the keyway.

Each form of key-adjusting means constitutes a take-up device cooperating with the key and with one of the cross-head parts, to maintain the key in binding engagement with key-engaging means provided by the side walls of the keyway, and to compensate for wear.

It will be seen that the shoe is confined against lengthwise movement in one direction, and against outward sidewise movement, by the engagement of its longitudinally tapered dovetail rib 17 with the side walls 15 of the longitudinally tapered dovetail groove in the body 12, and that the shoe is confined against endwise movement in the opposite direction by the bearing of the edges of the key on the side walls of the keyway. The key constitutes a one-piece locking element, and is a substitute for the plurality of bolts heretofore used to secure the shoe to the body, so that the number and cost of the essential parts, and the time required in assembling the same, and in compensating for wear, are materially reduced.

Owing to the tapering form of the key, a slight endwise adjustment thereof is sufficient to compensate for wear of the oblique edges of the key and the side walls of the keyway, so that such wear may be quickly compensated for by the simple operation of longitudinally adjusting the key.

The longitudinally extending dovetail joint elements may be reversed, as shown by Figures 9 and 10. Figure 9 shows a dovetail rib 17^a formed on the body 12, the keyway in said rib being designated by 18^a. Figure 10 shows the dovetail groove formed

in the inner face of the shoe, the bottom and side walls of the groove being designated by 14^a and 15^a. In this modification the key-receiving slots, here designated by 16^a, are formed in the shoe. The operation of assembling the parts and adjusting the key is as already described.

Owing to the fact that the undercut edge walls 15 of the groove 14 diverge from each other and impart a longitudinal taper to the groove, said walls collectively constitute a two-part end abutment cooperating with the correspondingly undercut and diverging edge walls of the rib 17, in limiting endwise movement of the shoe member in one direction, so that the shoe member is movable on the body member to an operative position determined by said two-part abutment. The shoe member is confined by said abutment along substantially its entire length, 85 the edge walls 15, constituting said abutment, performing the major portion of the duty of holding the shoe in its operative position. The opposed abutment formed by the one-piece key 20, is therefore required to 90 perform only the minor duty of confining the shoe against the two-part abutment. For the performance of this duty, the key 20, which may be quickly applied and removed, is sufficient.

I claim:

1. A locomotive cross head comprising, in combination, a body member, a shoe member removably seated on the body member, one of said members having a longitudinally extending dovetail groove, whose undercut edge walls diverge from each other from end to end of the groove, so that the groove is longitudinally tapered, the other member having a longitudinally extending dovetail rib 105 whose undercut edge walls diverge from each other from end to end of the rib, so that the rib is longitudinally tapered, the edge walls of the groove collectively forming a two-part abutment cooperating with 110 the edge walls of the rib to limit endwise movement of the shoe member in one direction only, so that the shoe member is movable on the body member to an operative position determined by said abutment, and is confined against outward side-wise movement by the interengagement of said walls, one member being provided with a transverse keyway, and a one-piece key separably connected with the body and extending through slots 120 formed in its reception for the other of said members, and through said key-way, said key constituting an end abutment confining the edge walls of the rib against the said two-part abutment, means being provided 125 for releasably securing the key in its operative position.

2. A locomotive cross-head comprising, in combination, a body portion, having a longitudinally extending dovetail groove, whose 130

undercut edge walls diverge from each other from end to end of the groove, so that the groove is longitudinally tapered, a shoe having a longitudinally extending dovetail rib, 5 whose undercut edge walls diverge from each other from end to end of the rib, so that the rib is longitudinally tapered, the rib being provided with a transverse keyway, the edge walls of the groove collectively forming a two-part abutment cooperating with the edge walls of the rib, to limit endwise movement of the shoe in one direction only, so that the shoe is movable endwise on the body to an operative position determined 10 by said abutment, and is confined against

outward sidewise movement by the interengagement of said edge walls, and a one-piece key separably connected with the body, and extending through the slots formed for its reception therein, and through the 20 keyway, said key constituting an end abutment cooperating with the keyway in confining the edge walls of the rib against the said two-part abutment, means being provided for releasably securing the key in its 25 operative position.

In testimony whereof I have affixed my signature.

HARRY GUEST.
